BOILER FOR HEATING SYSTEMS

Marvin W. Smith, Bath, Pa.

Application December 22, 1932, Serial No. 648,503

5 Claims. (Cl. 122—176)

This invention relates to boilers designed for heating houses by either hot water or steam heat and has for its object the provision of a boiler so constructed that it may be readily converted from a hot water heating boiler to a steam boiler or vice versa, and a further object is to provide a boiler of this character which is formed in units or sections so that it may be readily increased in heating capacity by the addition of further sections.

A further object is to provide a boiler of this character so constructed that the water in the boiler is subjected to the full heat of the fire and in which a maximum of heating surface is provided for the water.

A further object is to so construct the boiler that the water is not carried downward around the fire pot where it would be liable to be cooled by the relatively cold fuel and in which the fire will not be chilled by the cold water in the walls of the furnace.

Other objects will appear in the course of the following description.

My invention is illustrated in the accompanying drawings, wherein:

Figure 1 is a front elevation of a hot water boiler constructed in accordance with my invention;

Figure 2 is a fragmentary section on the line 2—2 of Figure 1;

Figure 3 is a section on the line 3—3 of Figure 2;

Figure 4 is a section on the line 4—4 of Figure 2;

Figure 5 is a front elevation partly broken away showing the manner in which my boiler may be converted into a boiler used for steam heating.

Referring to the drawings and particularly Figure 1, it will be seen that the boiler is formed primarily of five sections, the section A being the ash pit section, the section B the fire pot section, the sections C and D being heating sections and the section E being the cap section or crown of the boiler. Section A may be constructed in any suitable manner and is preferably of cast iron and is provided with the ash removing door 10. The upper end of the section A is flanged at 12 while the section B at its lower end is formed with the inwardly turned flange 13 confronting the flange 12 and engaged therewith in any suitable manner. The upper end of the section B is outwardly flanged at 14, this flange 14 also extending inward. Disposed between the flange 13 and the inwardly

extending portion of the flange 14 is a fire brick lining 15. A grate 16 is mounted in the section B, this grate being removable so that gas or oil burners may be used and being of any suitable construction which will permit the furnace to be used with various grades of coal.

The section C rests upon the section B and is outwardly flanged at its lower end to fit upon the flange 14 and be bolted thereto as shown clearly in Figure 1. The section C carries the charging door 17 having therein the usual damper 17a. The section C as shown in Figures 2 and 3 is formed with a hollow shell to define a water leg or space 18 defined by an outer and an inner wall. The upper wall or web 19 defining the upper end of the water space is grooved to receive a rib on the lower end of the section D as is shown clearly in Figures 2 and 3. The section D rests upon the section C and is formed of a hollow shell having an outer wall and an inner wall, the inner wall being designated 20. This inner wall does not lie parallel with the outer wall but is downwardly and laterally inclined with reference to the vertical axial center of the furnace, as shown most clearly in Figure 2 so that the water space 21 of this section D at the rear of the furnace is relatively wide at its lower end and at the front of the furnace is relatively wide at its upper end. The inner wall 20 thus defines a space which is eccentric at both ends to the vertical axis of the furnace.

The upper wall 22 of the water space 21a is formed with two screw-threaded openings 23 for the reception of the lower ends of the riser pipes 24. There are two of these pipes shown in Figure 1, these pipes carrying hot water off to the radiators or other heating system. The cap section E is hollow to provide a water space 25 and an angular nipple 26 opens through the upper wall of the water space 21 and opens into this space 25 as shown in Figure 2 at the rear of the furnace. There are preferably two or more of these nipples 26. This cap section E is also formed with the flue 27 whereby the products of combustion are carried to the chimney or stack.

Extending from front to rear of the section D and opening through the inner wall 20 of this section are the water heating tubes 28. There may be as many of these tubes as desired, the tubes being preferably arranged in staggered relation and relatively close together as in a water tube boiler so as to permit the products of combustion to pass around these tubes and heat the water therein. These tubes are at right angles to the wall 20 or, in other words, are upwardly

inclined with reference to a horizontal plane as shown in Figure 2. These tubes may be engaged at each end with the wall 20 in any suitable manner and expanded in the usual manner of such tubes into the sheet constituting the wall 20. It will be seen that these tubes take water from the rear of the section D, carry the water upward and forward into the front of the section D and discharge it in the upper portion of the water space contiguous to the riser pipes 24.

Disposed between groups of the water tubes 28 are the hollow baffles shown as two in number and designated 29 and 30. These extend parallel to the pipes. The baffle 29 extends from the rear of the wall 20 upward and forward and terminates short of the front of the wall 20 as shown clearly in Figure 2. The baffle 30 extends from the front of the wall 20 and terminates short of the rear of the wall 20 so that these baffles cause the products of combustion rising from the fire pot to take a circuitous course in passing around the water tubes 28 so that all of the tubes will be subjected to a maximum amount of heat and as much as possible of the heat may be abstracted from the products of combustion. Preferably the baffles 29 and 30 will be filled with water as shown and from the opposite ends of these baffles will extend pipes 31. These pipes 31 are shown as leading to the risers 24 but because of the fact that these pipes 31 extend out of the boiler, these pipes may be connected to hot water tanks in the manner of water backs.

Preferably the furnace will be rectangular in cross section and hence the inner wall 20 will be rectangular in cross section. Preferably the outer wall of the section D will be provided with plates 34 removably held in place by bolts 33. By removing these plates after, of course, all water has been drained from the boiler, it is possible to clean out the interior of section D. The baffles 29 and 30 may be supported in any suitable manner but, as shown, they are supported by the inwardly extending pipes 31 which constitute outlet pipes to the baffles and the return pipes thereto designated 43. These baffles, if anything should go wrong can be removed by removing some of the tubes and, of course, removing either the top or bottom sections.

Disposed within the water chamber 21a at the front of the furnace or boiler is a plate 35 supported by stay bolts 36 or in any other suitable manner, this plate extending vertically downward from a point beneath the lower ends of the pipes 24 and at its lower end being inwardly flanged as at 37, this flange extending inward and bearing against the wall 20 as shown in Figure 2. This plate 35 acts as a baffle directing the hot water from those tubes 28 above the baffle 29 directly up to the riser pipes 24. The advantages of this will be hereafter pointed out.

It will be noted from Figure 2 that the water space 18 is connected to the water space 21 by means of the exterior pipes 38. These pipes extend from the front of the water space 18 upward and rearward to the rear lower end of the water space 21. Connecting the rear of the water space 18 with the upper or middle portion of the rear of the water space 21 are one or more vertical pipes 39, and the upper rear portion of the water space 21 is connected by the angular nipples 26 previously described with the water space 25 in the cap section E. This water space 25 is in turn connected with the risers 24 by the pipes 40. It will be seen from Figure 4 that the wall 20 which is the inner wall of the water

space 21 extends around in spaced relation to the side wall and rear wall of the boiler but that the wall 20 is formed with flanges or webs 20a (see Figure 4) which extend laterally to the outer wall of the boiler so that the space 21a at the front of the boiler and into which the heated water is discharged is separated from the space 21 in which the water is heated and that the space 21 is connected to the space 21a by the water tubes 28.

Thus it will be seen that the water is heated in the water space 18, thence passes into the water space 21, thence the hottest water passes into the water space 25 over the top of the boiler and the water from space 21 passes through the tubes 28 into the space 21a and is thence carried off by the riser pipes 24 to the heating system.

In Figure 5, I have illustrated the manner in which my boiler may be slightly changed for use as a boiler for generating steam for steam heating systems and I have also illustrated in Figure 5 an additional section designated D' which may be inserted between the section C and the section D, thus illustrating the fact that a number 100 of sections such as D' might be disposed one above the other between the sections C and D.

In Figure 1, the pipes 31 leading from the baffles 29 and 30 are illustrated as being connected to pipes 41 which discharge into the riser pipes 24. It is to be understood, however, that the pipes 31 or the pipes 41 might be connected to a separate tank, as previously stated, so as to provide hot water for domestic purposes. The return pipes for the boiler are designated 42 in Figure 1 and these at their lower ends enter the lower end of the space 18. Branch pipes 43 lead into the lower ends of the baffles 29 and 30 so as to provide for a circulation of water through these baffles. Preferably and in order to prevent the water in the legs of the space 21 shown in Figure 4 from becoming trapped or dead without circulation, I provide openings 44 at the top of the space 21, these openings extending through the flange or web 20a into the space 21a.

With the form of the invention shown in Figures 1 to 4, it is obvious that water will pass into the lower portion of the space 18 which surrounds the fire pot through the return pipes 42 and that water will also be carried into the hollow baffles 29 and 30 by the pipes 43. The water within the space 18 as it is heated will pass up the pipe or pipes 38 into the lower end of the space 21 and will also pass up the pipe or pipes 39 into the space 21 and this water will pass 130 into the space 25 in the cap section. The water in this space 21 and in the space 25 will be heated by the upward passage of the products of combustion and water from the space 21 will pass upward through the water tubes 28 into 135 the space 21a at the front of the boiler and will be carried upward into the riser pipes 24, the water from the space 25 being carried into these riser pipes through the pipes 40.

In Figure 5, where I have shown, as before 140 stated, this boiler as being adapted for the generation of steam, the structure is precisely the same as in the hot water boiler previously described except as follows:—The dome section E' is deeper than the dome section E so as to provide a steam space in the upper portion of the dome section E'. A pipe or pipes 45 leads from the dome section E' to carry off the steam. The pipes 46 and 47 lead from the interior of the water space 21 and 21a into the dome E'. As 150

shown in Figure 5, an extra section D' is disposed between the sections C and D and under these circumstances, the water space of section C is connected to water space 21 of section B by 5 means of the pipe or pipes 39a which have the same function as the pipes 39. The upper end of the water space 18 is connected to the water space of the section D' by means of the pipe 38a which has the same function as the pipe 10 38 in Figure 2 and the water space 21a of section D' is connected by a pipe 48 to the upper portion of the water space 21a of section D. The action of this boiler is precisely the same as heretofore described except that steam will gather in the 15 upper portion of the dome E' and this steam will be carried off through the riser pipe 45. Of course, suitable pressure gages will be attached to this dome.

It will be seen that with this boiler, the water 20 is prevented from rising directly in the riser pipes but must take a circuitous course and pass through the water tubes 28 and thus abstract all the heat possible from the fire before passing into the discharge pipes 24. The boiler is readily 25 assembled and may be readily enlarged by using one or more of the small units D' in conjunction with the units D and C.

Preferably the outer walls of the front of the boiler will be formed by plates 49 as shown best 30 in Figure 2 held to the body of the boiler by screws, bolts or the like, the baffle plate 35 being attached to a plate 49 so that when this plate 49 is removed, of course, the boiler having been drained before, access may be had to the pipes 35 28 to permit these pipes to be cleaned out or permit new pipes to be inserted. Removable plugs 50 are provided at all corners of the boiler for cleaning purposes.

The advantages of my invention over any hot 40 water or steam heating system known to me are many. The heater is so constructed that very little machine work is necessary as there are no drums or tanks connected with it as such drums or tanks are very expensive. The circulating 45 water travels through tubes 28 directly up the heating system not even going into the dome E which I believe to be entirely unnecessary. The more water there is above the heater, the slower the circulation is because the water is 50 hottest around the fire box and lower rows of tubes. When water is circulated through large drums or tanks, it is checked in its circulation because the water in the drum or tank does not 55 get the same amount of heat as was present in the water in the lower part of the boiler. The brick work 15 in the lower portion of the heater is, I believe, a great advantage over other heaters, and further by having the water circulating to the back part of the boiler is of advantage because 60 the pitch of the tubes secures a higher velocity and the more pitch which is given to these circulating tubes, the higher the velocity. With my construction, I have provided a plate 35 to take the hottest water up through the system and not through domes or tanks. By having the tubes inclined, the water circulates one way through the heater, whereas if the tubes 28 were level, circulation would be slow because of the 65 tendency of the water to flow in both directions. By adding an additional section to increase the heating as shown most clearly in Figure 5, this section gets the first heat and as the water in this section gets heated and starts to circulate, it will 70 go directly to the water space 21a and riser pipes 24 throughout the system and not go from one

section or the other or to large drums or tanks which is a waste of time and energy. With my construction, I provide a relatively small dome because the combustion is not nearly as hot as below the tubes. Baffle 29 gets the same amount 80 of heat as do the lower tubes and, therefore, is connected direct to the riser pipes 24. These baffle plates perform two functions, namely as baffle plates for the purpose of causing the heat to circulate from front to rear and then back 85 again and also as water heaters.

Another advantage of my construction resides in the fact that the steam or vapor dome is so connected to the tube sections that a continuous circulation is secured. As previously stated, there 90 is very little machine work connected with this construction as my sections are all connected together with pipes. Where a boiler is formed of a plurality of sections connected to each other by ferrules, the construction is very expensive 95 because the outlets and inlets from one section to the other must be machined out and put together with copper or brass ferrules. With my construction by removing the plate 49, access can be had to all the tubes and furthermore this construction is less expensive than if a solid casting were used which had to be tapped and plugged for each tube. Excluding the dome E, and the ash pit and fire box, my boiler has but three 100 sections, namely the sections C, D and if necessary D'.

The section D' will be built in different sizes and the sections will have from two to eight rows of tubes, just depending upon the size of the sections.

While I have illustrated plates 34 whereby access may be had to the interior of the water space of section D, it is to be understood that section D need not be provided with these plates 34 but that the outer walls may be entirely solid.

While I have illustrated a preferable form of my invention, I do not wish to be limited thereto as obviously many changes might be made therein without departing from the spirit of the invention as defined in the appended claims.

I claim:

1. A boiler having a fire box and an ash pit, a section resting on the fire box and having a hollow shell to provide a water space, a section resting on the first named section and having a hollow wall enclosing a front and rear water space separated from each other, the rear water space having water legs extending along the sides of this section, water tubes extending upward from the rear water space and extending into the front water space, outlet pipes extending from the upper end of the front water space, return pipes connected to the water space of the first named section, a connection leading from the front of the water space of the first named section to the rear water space of the second named section at the lower end thereof, a tubular connection leading from the rear upper end of the first named section and discharging into the middle of the rear water space of the second named section, a hollow top section with which the upper section of the boiler communicatively connects, and an outlet pipe leading therefrom.

2. A boiler having a fire box and an ash pit, a section resting on the fire box and having a hollow shell to provide a water space, a section resting on the first named section and having a hollow shell enclosing a front and rear water space separated from each other, the rear water space having water legs extending along the sides

- of this section, water tubes extending upward from the rear water space and extending into the front water space, outlet pipes extending from the upper end of the front water space, return pipes connected to the water space of the first named section, a connection leading from the front of the water space of the first named section to the rear water space of the second named section at the lower end thereof, a tubular connection leading from the rear upper end of the first named section and discharging into the middle of the rear water space of the second named section, a hollow top section with which the upper section of the boiler communicatively connects, an outlet pipe leading therefrom, and upper and lower baffles extending transversely across the interior of the second named section, the lower baffle extending from the front toward the rear, terminating short of the rear, the upper baffle extending from the rear toward the front but terminating short of the front, the baffles separating the water pipes into groups, and pipes whereby water may be circulated through said baffles, said pipes extending out of the boiler.

3. A boiler having a fire box and an ash pit, a section resting on the fire box and having a hollow shell to provide a water space, a section resting on the first named section and having a hollow shell enclosing a front and rear water space separated from each other, the rear water space having water legs extending along the sides of this section, water tubes extending upward from the rear water space and extending into the front water space, outlet pipes extending from the upper end of the front water space, return pipes connected to the water space of the first named section, a connection leading from the front of the water space of the first named section to the rear water space of the second named section at the lower end thereof, a tubular connection leading from the rear upper end of the first named section and discharging into the middle of the rear water space of the second named section, a hollow top section with which the upper section of the boiler communicatively connects, an outlet pipe leading therefrom, and upper and lower baffles extending transversely across the interior of the second named section, the lower baffle extending from the front toward the rear, terminating short of the rear, the upper baffle extending from the rear toward the front, the baffles separating the water pipes into groups, and pipes whereby water may be circulated through said baffles, said pipes extending out of the boiler.

4. A boiler having a fire box and an ash pit, a section resting on the fire box and having a hollow circumferential shell to provide a circumferential water space closed at its upper and lower ends, a section resting on the first named section and having a hollow circumferential shell divided to provide two water spaces, one at the front and one at the rear of the boiler, said water spaces together extending circumferentially around the entire boiler, water tubes extending across the interior of this last named section and opening at their opposite ends into the two water spaces, outlet pipes extending from the upper end of the front water space, return pipes connected to the water space of the first named section, a hollow top section resting upon the upper section of the boiler and communicatively connected with the rear water space of the second named section and having an outlet pipe and a flue, and pipes communicatively connecting the water space in the first named section with the rear water space of the second named section at different levels, said connecting pipes being disposed upon the exterior of the furnace.

5. In a boiler, a section having a hollow peripheral shell divided to provide two water spaces, water tubes extending across the interior of the section and opening into said spaces, and hollow baffles having staggered relation to each other and extending across the interior of the section, the baffles being separate from the section, and water circulating pipes extending through the boiler shell and constituting supports for the baffles, and means whereby water may be supplied thereto.
